UNITED STATES PATENT OFFICE.

HAROLD STEWART, OF WALLA WALLA, WASHINGTON, ASSIGNOR TO STEWART-KELLY
AUTOMATIC DRAIN VALVE COMPANY, OF WALLA WALLA, WASHINGTON.

THERMAL VALVE.

1,161,013.

Specification of Letters Patent. Patented Nov. 16, 1915.

Application filed August 3, 1914. Serial No. 854,780.

To all whom it may concern:

Be it known that I, HAROLD STEWART, a citizen of the United States, residing at Walla Walla, in the county of Walla Walla 5 and State of Washington, have invented certain new and useful Improvements in Thermal Valves, of which the following is a specification.

The valve which is the subject-matter of 10 the present application for patent is designed more particularly for use in connection with automobile radiators to prevent injury by freezing of the water, the valve automatically opening to drain the radiator 15 whenever the temperature drops to the freezing point. It may be here stated that the invention is not limited to automobile radiators, but may with equal facility be applied to other water containers or piping 20 systems liable to damage by freezing.

The invention has for its object to provide a simple and efficient valve of the kind stated, and to this end it consists in a novel combination and arrangement of parts to be 25 hereinafter described and claimed, reference being had to the accompanying drawings in which—

Figure 1 is an elevation showing the application of the valve to an automobile 30 radiator; Fig. 2 is a central vertical section of the valve, and Figs. 3 and 4 are diagrams of the electric circuits employed.

Referring specifically to the drawings, 10 denotes a pipe connected to the radiator 11 35 of an automobile. In order to drain the radiator when the temperature drops to the freezing point and thus prevent injury to the radiator, or to the piping system and the water jacket of the engine, there is provided an automatic drain valve which is 40 constructed as follows: The casing of the valve is indicated at 12. The upper end of the casing is closed by a gap 13 having a nipple 14 for connection to the pipe 10, 45 through which nipple the water enters the casing. In the center of the casing is mounted a drain tube 15 having at its upper end an enlarged portion 16 which seats in a corresponding enlarged portion 17 of the valve 50 casing and is held in place therein by the cap 13. This drain tube is in line with the inlet through the nipple 14 and its upper end is open so that the water which enters the valve casing may flow down the tube. The 55 lower end of the tube is also open and has

a seat 18 for a valve 19, the latter being a ball, as shown in Fig. 2. The valve is carried by a stem 20 which depends from the valve and is connected at its lower end to the armature 21 of an electro-magnet mounted in the valve casing, the drain tube being located in the center of the core 22 of the magnet, said core having a longitudinal opening to accommodate the tube. The winding of the magnet is shown at 23. On the outside of the valve casing 12 is mounted a block 24 of insulation carrying binding posts 25, 26 and 27, respectively. The binding post 25 is connected by a insulated wire 28 to one end of the magnet winding 23, the other end of which latter passes through a piece 29 of insulation and is electrically connected to a spring 30 having a platinum contact point 31 designed to make contact with a platinum contact point 32 on the armature 21. The armature has a hole 33 to accommodate the insulation 29, which acts as a guide to keep the contact points 31 and 32 in line. The armature extends across the lower end of the drain tube 15 and has openings 34 registering with said end of the tube to permit the water to flow through when the valve 19 is unseated. In the drain tube 15 is located a thermal switch for controlling 35 the magnet circuit. This switch comprises a thermometer 35 in the casing of which is mounted, so as to move with the mercury column, a platinum wire 36 having a glass insulation 37 and a contact point 38 at its upper end. The upper end of the thermometer casing or tube has a bulbous enlargement 39 in which the contact point 38 is located. Across the bulb 39 extends a wire contact 40 with which the point 38 makes contact when the mercury column drops as 40 it indicates the freezing point. The contact 40 is connected by an insulated wire 41 to the binding post 26, from which latter a conductor 42 leads to one side of a battery 43 or other suitable source of electric energy. The other side of the battery is connected by a conductor 44 to the binding post 25. The mercury in the thermometer tube is electrically connected by an insulated wire 45 to the valve casing 12 at 46 and the armature is in 45 electrical contact with the valve casing, the lower end of the latter having an outlet tube 47 in which a sleeve 48 depending from the armature is slidably mounted. The binding post 27 is electrically connected to the valve 50 55 60 65 70 75 80 85 90 95 100 105 110

casing 12, and also connected by a conductor 49 to a push button or other switch 50 mounted on the dash 51 of the car as shown in Fig. 1. The switch is wired to the conductor 42 as indicated at 52. The lower end of the valve casing 12 carries a slidable spring latch pin 53 insertible into the outlet tube 47 to engage the bottom of the sleeve 48 and thus hold the valve 19 open. The thermometer 10 is held in place in the tube 15 by being mounted between two coiled springs 54 which prevents injury from jars and jolts.

The operation is as follows: When the temperature is above the freezing point, the contacts 38 and 40 are separated, and the magnet circuit is broken. The armature 20 has dropped down and carried the valve 19 to its seat, and the points 31 and 32 are in contact. The drain is now closed. When the temperature falls to 34° or, in other words, is slightly above the freezing point, the mercury column, upon descending in the thermometer tube, brings the contact 38 down against the contact 40, thus closing the magnet circuit. The circuit may be traced as follows: from one side of battery 43 by conductors 42 and 41 to contacts 38 and 40, mercury column in thermometer, ground wire 45 to valve casing 12, contacts 32 and 31, spring 30, magnet winding 23, wire 28, binding post 25, and thence by the way of conductor 44 to the other side of the battery. The magnet being now energized, its armature 21 is attracted, and as said armature carries the valve 19, the latter is unseated to open the drain. At the end of the travel of the armature the latch pin 53 shoots forward and comes beneath the bottom edge of the sleeve 48 and thus holds the armature in position to keep the valve open, this being necessary as the magnet circuit is broken by the separation of the points 31 and 32, which takes place when the armature starts to move. The magnet circuit is thus broken at the points 31 and 32, and a waste of current is prevented.

To fill the radiator after it has been drained, the latch pin 53 is withdrawn, which allows the armature 21 to drop, carrying the valve 19 back to its seat, and placing the points 31 and 32 in contact.

The conductors 49 and 52 allow the magnet circuit to be closed regardless of the temperature, so that the drain valve may be opened at will. When the switch 50 is closed, the magnet is energized, the circuit being as follows: from one switch point to battery 43 by conductor 52, to magnet winding 23 by conductors 44 and 28, spring 30, contacts 31 and 32, armature 21, and thence by conductor 49 to the other switch point.

I claim:

1. A thermal valve comprising a casing having an inlet and an outlet, a drain tube open at one end to the inlet and having at

its opposite end a valve seat opening to the outlet, a valve for said seat, an electro-magnet to the armature of which the valve is connected, an electric circuit in which the magnet is interposed, said circuit including a source of electric energy, and a thermal switch in the magnet circuit, the thermal element of said switch being mounted in the aforesaid tube. 70

2. A thermal valve comprising a casing having an inlet and an outlet, a drain tube open at one end to the inlet and having at its opposite end a valve seat opening to the outlet, a valve for said seat, an electro-magnet to the armature of which the valve is connected, said magnet being located in the valve casing and its core having an opening in which the drain tube is mounted, an electric circuit in which the magnet is interposed, said circuit including a source of electric energy, and a thermal switch in the magnet circuit, the thermal element of said switch being mounted in the aforesaid tube. 75 80

3. A thermal valve comprising a casing having an inlet and an outlet, a drain tube open at one end to the inlet and having at its opposite end a valve seat opening to the outlet, a valve for said seat, an electro-magnet to the armature of which the valve is connected, said magnet being located in the valve casing, and its armature being adjacent to the outlet end of the tube and having a fluid passage, an electric circuit in which the magnet is interposed, said circuit including a source of electric energy, and a thermal switch in the magnet circuit, the thermal element of said switch being mounted in the aforesaid tube. 85 90 95

4. A thermal valve comprising a casing having an inlet and an outlet, a drain tube open at one end to the inlet and having at its opposite end a valve seat opening to the outlet, a valve for said seat, an electro-magnet to the armature of which the valve is connected, said magnet being located in the valve casing and its core having an opening in which the drain tube is mounted, the armature of the magnet being adjacent to the outlet end of the tube and having a fluid passage, an electric circuit in which the magnet is interposed, said circuit including a source of electric energy, and a thermal switch in the magnet circuit, the thermal element of said switch being mounted in the aforesaid tube. 105 110 115

5. A thermal valve comprising a casing having an inlet and an outlet, a drain tube open at one end to the inlet and having at its opposite end a valve seat opening to the outlet, a valve for said seat normally in closed position, an electro-magnet to the armature of which the valve is connected, said magnet being located in the valve casing and its core having an opening in which the drain tube is mounted, an electric circuit in which the 120 125 130

the magnet is interposed, said circuit including a source of electric energy, a thermal switch in the magnet circuit, the thermal element of said switch being mounted in the aforesaid tube, and a latch carried by the valve casing and engageable with the armature for locking the same in position to hold the valve open after the latter has been operated.

6 10 6. A thermal valve comprising a casing having an inlet and an outlet, a valve controlling the outlet, an electro-magnet to the armature of which the valve is connected, and said armature being electrically connected to the valve casing, a thermal switch having one side grounded on the valve casing, a source of electric energy to one side of which the other side of the thermal switch is connected, the other side of said source of electric energy being connected to one end of the magnet winding, a contact to which the other end of the magnet winding is connected, a contact on the armature located opposite the aforesaid contact, and an auxiliary switch having connection with the valve casing and with that side of the source of electric energy to which the second-mentioned side of the thermal switch is connected for closing the magnet circuit independent of the thermal switch.

7. A thermal valve comprising a casing having an inlet and an outlet, an electro-magnet in the casing, the core of said magnet having an opening which is in line with the inlet and outlet of the casing, a valve seat in said core opening, a valve for said seat carried by the armature of the magnet, an electric circuit in which the magnet is

interposed, said circuit including a source of electric energy, and a thermal switch in the magnet circuit, the thermal element of said switch being in the core opening.

8. A thermal valve comprising a casing having an inlet and an outlet, an electro-magnet in the casing, the core of said magnet having an opening which is in line with the inlet and outlet of the casing, a valve seat in said core opening, a valve for said seat carried by the armature of the magnet, said armature having a fluid passage, an electric circuit in which the magnet is interposed, said circuit including a source of electric energy, and a thermal switch in the magnet circuit, the thermal element of said switch being in the core opening.

9. A thermal valve comprising a casing having an inlet and an outlet, an electro-magnet in the casing, the core of said magnet having an opening which is in line with the inlet and outlet of the casing, a valve seat in said core opening, a valve for said seat carried by the armature of the magnet, an electric circuit in which the magnet is interposed, said circuit including a source of electric energy, a thermal switch in the magnet circuit, the thermal element of said switch being in the core opening, and a latch carried by the casing and engageable with the armature for holding the same in position to keep the valve open.

In testimony whereof I affix my signature in presence of two witnesses.

HAROLD STEWART.
